MULTIPLE SLAT TYPE FOLDING DOOR

Philip M. Paulsrude, Shelton, Wash., assignor to Wood Specialty Products, Inc., Mountlake Terrace, Wash.

Filed Dec. 17, 1958, Ser. No. 781,121

7 Claims. (Cl. 160—183)

This invention relates to a multiple slat type folding door, and this application is a continuation-in-part of my earlier application, Serial Number 476,789 filed December 21, 1954, now abandoned.

An object of this invention is to provide an efficient and ornamental multiple slat type folding structure of fairly solid material, such as wood, which can be used as a door in a doorway or which can be used in other ways for partitioning off or dividing space in a building or other structure.

Another object of this invention is to provide a vertical slat type folding door which is space saving in that it operates like a draw curtain and does not require any space in which to swing.

Other objects are to provide a non-pliable folding door which is inexpensive to manufacture, which is durable and long lasting, which is easy to install and easy to operate and which forms an attractive appearing, efficient and substantial closure for an opening.

Another object is to provide a multiple slat folding structure in which adjoining edges of adjacent slats are rounded and have longitudinal grooves which, considered cross sectionally of the slats, are of keyhole shape and are offset relative to the medial plane of the slats and in which the edge portions of adjacent slats are hinged together by connector strips each comprising two parallel bead portions seated in the wider parts of the grooves of the adjoining slats and connected by a thinner pliable web portion, the grooves being positioned and arranged so that the unfolding or extension movement of the slats is checked by the connector strips before said slats reach a common plane and while the slats are still at an angle or inclined herringbone fashion relative to each other.

Other objects of this invention will be apparent from the following description taken in connection with the accompanying drawings.

In the drawings,

Fig. 1 is a front elevation on a small scale of a double folding door constructed in accordance with my invention showing a door at one side of a doorway folded and a door at the other side of the doorway extended.

Fig. 2 is a view in cross section showing a plurality of door slats in fully extended or "closed door" position and showing parts of the door frame with which the said slats are connected.

Fig. 3 is a sectional view similar to Fig. 2 showing a plurality of the door slats in a folded or "open door" position.

Fig. 4 is a fragmentary sectional view showing the top portion of a door frame together with means for suspending the slats of a door therefrom.

Fig. 5 is a detached fragmentary perspective view showing a piece of flexible connector strip used to hinge together adjacent edge portions of the door slats.

Fig. 6 is a fragmentary sectional view on a larger scale than Figs. 2 and 3 showing the hinged edge portions of two adjacent door slats as they would appear when fully extended.

2

Fig. 7 is a view similar to Fig. 6 but showing two adjacent slats folded in face to face relation.

Fig. 8 is a view in cross section showing an edge portion of one of the slats with the connector strip omitted.

Fig. 9 is a fragmentary sectional view showing a modified form of my invention.

Fig. 10 is a view similar to Fig. 2 but showing a modified form of connector strip by which the slats are spaced apart when the slats are extended to provide a modified appearance.

Fig. 11 is a view similar to Fig. 3 and showing the folded arrangement of the slats and connector strips of the modification shown in Fig. 10.

Like reference numerals designate like parts throughout the several views.

In a general way this invention comprises an accordion type folding slat structure composed of a plurality of non-pliable slats 10, preferably of wood, and hinged together in edge to edge relation by pliable connector means so that the slats may be compactly folded face to face or may be unfolded or extended or opened out into a position in which said slats are more nearly in edge to edge relation but in which adjoining slats are still inclined herringbone fashion relative to each other so that they present a pleated or accordion effect which is pleasing in appearance.

Each slat 10 is provided with rounded edge portions 11 and each edge portion 11 which is to be connected with another slat is provided with a longitudinally extending groove, it being understood that the outermost edge portion of each marginal slat of a group will not need to be grooved. Each groove comprises a part 12 of narrow width which extends from the exterior of that slat inwardly and terminates in a wider bottom part 13. Preferably this wider bottom part 13 is approximately cylindrical but obviously it can be otherwise shaped as long as it is wider than the part 12 of the groove. Preferably the edges at opposite sides of the entrance to the groove 12 are slightly rounded, as shown by 14, Fig. 8.

Each groove 12, 13 extends throughout the length of the slat and is of approximately keyhole shape, considered cross sectionally of the slat. The broken line x—x in Fig. 8 indicates the medial plane of the slat 10 and this plane intercepts the curved edge of the slat at point y. The grooves 12, 13 are offset around the curved edge of the slat so that the entrance or mouth of each groove is positioned a substantial distance from the point y. This offsetting of the grooves 12, 13 around the curved edge of the slat helps to provide a construction in which the opening movement of the slats relative to each other is limited, as hereinafter explained.

The slats 10 are connected together edge to edge by pliable connector strips each formed of two parallel spaced apart edge beads 15 connected with each other by an integral web part 16. The edge beads 15 seat within the wider bottom parts 13 of the grooves and the thinner web 16 is disposed within the narrower parts 12 of the grooves and the connector strips thus form a pliable hinge connection which extends from end to end of the slats and precludes the possibility of an open crack between the slats. The edge beads 15 are firmly anchored in the wider parts 13 of the grooves and will not pull out of these grooves and it is not necessary to cement the connector strips in the grooves. The connector strips may be of any desired color and any visible portions of these strips will tend to add to the ornamental appearance of the door. At least the web part 16 of the connector strips is preferably slightly elastic.

The connector strips 15, 16 may be threaded or drawn into the grooves from the ends of the slats and the lower ends of the grooves may be closed by plugging or by

applying caps or plates to the lower ends of the slats. This will prevent the connector strips from working down in the grooves.

One manner of connecting this folding door to a door frame 17 is shown in Figs. 2 and 3. In this illustration two narrow slats 10a and 10b, which preferably are half the width of the slats 10, are provided at one edge of the folding door and the outermost narrow slat 10a is rigidly secured, as by screws 18, to the door frame 17. With this arrangement the door, when extended as shown in Fig. 2, will be midway between the two sides of the door frame 17. Obviously one of the full width slats 10 can be secured directly to the door frame, in which instance the door, when extended, will be offset to one side of the medial plane of the door frame.

Each slat is supported or suspended from the header or top part 19 of the door frame by a hollow track 20 which receives rollers or gliders 21. These gliders or rollers 21 are carried by T-shaped hangers 22 which are secured to the upper end portions of the slats.

Opening and closing of these doors can be facilitated by providing hand hold means 23 of any suitable type on the marginal slat of the door, see Fig. 1. The doors will ordinarily remain in an extended position, but if desired, the hand hold means 23 may be of a magnetic type or other means may be used to hold said doors extended or in "closed door" position.

Fig. 9 shows a modified form of my invention in which slats 25 similar to the slats 10 are provided with grooves 26 which are wider at their bottoms and narrower at the locations where they intercept the surfaces of the slats and which are positioned in the slats similarly to the grooves 12, 13. These grooves 26 are adapted to receive connector strips which comprise wider marginal bead portions 27 connected by a thinner pliable web portion 28. The form of invention shown in Fig. 9 functions similarly to the previously described structure shown in Figs. 1-8.

In the modification illustrated in Figs. 10 and 11, the only difference over the embodiment shown in Figs. 1-8, resides in the provision of a web part 16' of greater lateral width. By this arrangement the interconnected slats 10 are spaced apart laterally when extended, thereby rendering the webs visible from both sides of the door assembly.

In both of the embodiments illustrated, it is the oblique arrangement of the grooves 12, 13 with respect to the medial plane of the slats, that limits the included angle between adjacent slats of the assembly to less than 180°. Thus, in Fig. 10 the slats are shown in fully extended condition, achieved by pulling upon the hand hold means 23 (Fig. 1) in the direction opposite the door frame 17, to the maximum limit at which the exposed portions of the webs 16' and the hangers 22 lie on a common rectilinear plane. This plane is illustrated in Figs. 10 and 11 by the dash line 20' which represents the longitudinal axis of the supporting track 20. Any further pulling force on the hand hold means 23 to cause further extension of the slats, functions merely to stretch the exposed portions of the webs 16' along this plane. Hence, since the grooves 12 at opposite sides of each slat emerge exteriorly on opposite sides of the medial plane of the slat, it is apparent that the included angle between adjacent slats in the fully extended assembly, is always less than 180°.

The foregoing condition also obtains in the embodiment illustrated in Figs. 1-8, for it is evident that if sufficient force is applied to the hand hold means 23 in the direction opposite the frame 17, the elastic web 16 may permit separation of the abutting edges 11 of adjacent slats, until the maximum condition of extension illustrated in Fig. 10 is achieved. Thus, whether the webs are proportioned in width to effect either abutment of the slat edges 11, as in Fig. 2, or separation thereof as in Fig. 10, at full extension of the assembly, the zig-zag or herringbone arrangement of slats is maintained,

and the only difference resides in the maximum degree of included angle between adjacent slats and the ornamental effect achieved either by closing the space between adjacent slats (Fig. 2) so as to expose the web 16 only on one side of the assembly, or by exposing the web to view from both sides, as shown in Fig. 10. In either case, all of the slats in an assembly are positioned at a uniform angle relative to each other, for most pleasing appearance when the assembly is extended, and the slats automatically move into face to face abutment upon collapsing of the assembly to "open door" position.

Folding of the slats in the predetermined face to face relationship illustrated is assisted by the pivotal suspension of the slats from the track 20 by means of the hangers 22. Since the hand pressure applied in the direction of the door frame 17 is exerted on the end of the terminal slat which is disposed obliquely with respect to the plane 20', said terminal slat tends to rotate about the pivot hanger 22, thus initiating the rotation of the intermediate slats in the direction to reduce the included angle between adjacent slats. Moreover, since each of the slats is supported pivotally from the track 20, they are constrained against lateral movement which, in the absence of pivotal support, might cause random buckling of the slats outwardly from the plane of the door opening.

The door of this invention saves space, operates easily, folds compactly, is decorative and attractive in appearance and is fairly strong and substantial in construction. The slats are easily connected together by the connector strips and the strips do not require any cementing. This makes it possible to add or detach slats during installation and thus adapts this structure to openings of varying widths. For narrow doorways only one of these doors need be used.

The foregoing description and accompanying drawings clearly disclose preferred embodiments of my invention, but it will be understood that this disclosure is illustrative and that changes may be made within the scope and spirit of the following claims.

I claim:

1. A folding panel for use as a door and partition comprising a plurality of edge to edge adjacent rigid slats, the edge of each slat which adjoins another having a longitudinally extending diagonal edge groove, said groove being narrow at the surface of the slat and expanding in width inwardly of the slat, the opening of each groove at the surface of the slat being offset from the medial plane of the slat, the grooves in opposite edges of the slat opening toward opposite sides of the slat, a connector strip connecting adjoining edges of each pair of slats, each connector strip comprising two thicker edge portions seated in the wider part of the grooves of adjoining slats and a thinner pliable web part extending between the two thicker edge portions and pivotally connecting the slats, the grooves in adjoining edge portions of adjoining slats being on the same side of the panel and alternate pairs of grooves and a connector strip engaged therein being on opposite sides of the panel, each connector strip providing parallel face to face folding of two slats that it connects but when the panel is extended, normally maintaining the two slats that it connects at an angle of less than 180° with respect to each other to maintain the slats of the panel in substantially uniform zigzag relation.
2. The folding panel of claim 1 including suspending means projecting from the upper end of the slats for slidably suspending the slats pivotally from an overhead support and for guiding the slats across the opening during the folding and unfolding of the slats.
3. The folding panel of claim 1 wherein the width of the web part of the connector strip is proportioned to cause abutment of the adjacent edges of adjoining slats when the slats are extended.
4. The folding panel of claim 1 wherein the width of the web part of the connector strip is proportioned to

space apart the adjacent edges of adjoining slats when the slats are extended.

5. A folding panel for use as a door and partition for an opening, comprising more than two adjacent parallel upright slats, means for securing one of the end slats to a support defining the opening, each of the adjacent longitudinal edges of adjacent slats being provided with a longitudinally extending diagonal groove, each groove being narrow at the surface of the slat and wider at its inner end, the opening of each groove being positioned laterally from the line where the medial plane of the slat intercepts the edge thereof, the grooves at the opposite edges of a slat opening toward opposite sides of the slats, adjacent slats being arranged with their adjacent grooves opening toward the same side of the slats, a connector strip connecting adjacent edges of adjacent slats, each connector strip comprising two thicker edge portions seated in the wider parts of the grooves in adjacent slats and a thinner flexible web part extending between the two thicker edge portions and pivotally interconnecting the slats, the off-center arrangement of the groove openings positioning the web part of the connector strip laterally from the medial plane of the connected slats, thereby limiting relative angular unfolding movement of adjacent slats to less than 180° and initiating

folding of adjacent slats in predetermined substantially parallel face to face relation, an overhead guide track adapted for mounting on an overhead support defining the opening, and suspending means projecting from the upper end of the slats and slidably engaging the guide track for suspending the slats pivotally from the track, the track guiding the slats across the opening during folding and unfolding of the slats.

10. The folding panel of claim 5 wherein the width of the web part of the connector strip is proportioned to cause abutment of the adjacent edges of adjoining slats when the slats are extended.

15. The folding panel of claim 5 wherein the width of the web part of the connector strip is proportioned to space apart the adjacent edges of adjoining slats when the slats are extended.
